CLAIM

The ornamental design for an electric shaver, as shown and described.

DESCRIPTION

FIG. 1 is a front view of an electric shaver, showing my new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is a front, top and right side perspective view thereof;

FIG. 8 is a front view thereof, shown with the cap removed to show portions not clearly visible when combined; and, FIG. 9 is a front, top and right side perspective view thereof. The broken lines shown in the drawings illustrate portions of the electric shaver that form no part of the claimed design.

1 Claim, 8 Drawing Sheets
